Primary Examiner — David Muller(74) *Attorney, Agent, or Firm* — Pamela L. Stewart(57) **CLAIM**

The ornamental design for a dental syringe, as shown and described.

DESCRIPTION

FIG. 1 is a perspective showing the new design for a dental syringe.

FIG. 2 is a right side view of the design shown in FIG. 1, the left side being a mirror image thereof;

FIG. 3 is a top view thereof;

FIG. 4 is a bottom view thereof;

FIG. 5 is a front view thereof; and,

FIG. 6 is a back view thereof.

The broken line showing of parts of the drawings is included for the purpose of illustrating use and environment and forms no part of the claimed design.
